UNITED STATES PATENT OFFICE.

CHARLES H. J. DILG, OF NEW YORK, N. Y.

DRAWER GUARD.

Application filed September 10, 1927. Serial No. 218,625.

My invention relates in general to articles of furniture, and particularly to articles having drawers therein.

My invention provides means, cooperating with a drawer, for protecting the contents thereof against displacement in the course of the movement of the drawer. It is a not infrequent occurrence that the contents of drawers, particularly such articles as papers and documents, are displaced from drawers and lost within the waste spaces of the cabinet. This occurs most easily when the drawer is full of papers, so that the natural elasticity of the pile of paper carries the uppermost one against the surfaces next above the drawer. If these surfaces are the top of the deck or the bottom of a superposed drawer, it may easily happen that the friction of the paper against the surface drags it out of the drawer in the course of opening of the drawer, and it falls down into spaces at the back and is thereby lost or misplaced.

My invention provides a drawer guard, adapted to cooperate with a drawer to prevent the occurrence of such mischance. It comprises a guard plate, preferably of sheet metal, or of wire, pivoted within the drawer, and provided in some embodiments with a spring to raise it to an elevated position where it will be out of the way as much as possible. The contents of the drawer may then be positioned under the guard and when so placed are held and prevented from being unintentionally pushed out of the drawer by any mischance.

Other objects and structural details of my invention will be apparent from the following description when read in connection with the accompanying drawings, wherein:

Fig. 1 is a perspective view of a desk having a drawer equipped with the guard of my invention;

Fig. 2 is a vertical section of the same embodiment, and

Fig. 3 is a developed view of the sheet metal guard member of the same embodiment.

Referring to the drawings, a desk consisting of a top member 1, upright members 2, and panel members 3 may be provided with drawers 4 and 5. Within the drawers, the guard member of my invention may desirably be positioned.

The guard member 6 is desirably formed of sheet metal as shown in Fig. 3 and may consist of a flat portion as shown, with end members 7 having pivot openings 8. The end

members are desirably bent along the lines 9 so that they assume positions parallel to each other, and at right angles to the flat portion. The length of the flat portion or cross member is desirably adjusted to be substantially that of the inside width of the drawer, and appropriate pivots, which may be wood screws 11, are provided, passing through the pivot holes 8 into wood of the sides of the drawers. Slots 12 and stops 14, which may also be wood screws may be provided to limit the upward and downward motion of the guard. A spring 15 may desirably be provided to hold the guard in appropriate operative position.

The guard members may vary in number according to the requirements imposed. A guard 6 is desirably provided at the rear of the drawer, and equipped with spring 15 and stop members 12 and 14 as indicated.

When so provided the guard is held in a raised position, with the edge of the flat portion against the surface under which it moves, and accordingly no crevice is left through which papers can pass and be lost. A second similar guard may desirably be provided at the front end of the drawer, if it is anticipated that large numbers of papers will be stored therein.

The rear guard 6 is also adapted to perform the additional function of a stop, to prevent travel of the drawer beyond a reasonable forward distance, so that there is no danger of falling out with its contents, and that no undue strains are imposed upon the furniture by lever effect of the unsupported portion of the drawer when fully opened.

In the operation of my device, the papers may be passed backward into the drawer and under the rear guard 6. The spring 15 holds the guard upward against the adjacent superposed surface, as of the desk top 1, and there is accordingly no space through which the papers can be drawn by the forward movement of the drawer. The close contact between the edges of the guard 6 and the under surface of the desk top 1 gives a scraping action which prevents papers adhering thereto. Likewise the presence of the guard 6 prevents the drawer being removed unintentionally since it comes in contact with a strip or guide 16, of the desk frame, in cooperation with which it acts as a stop to prevent too much forward movement of the drawer. However, in the event that it is desired to remove the drawer, the guard 6 may be pulled

downward by hand, below the level of the drawer, whereafter the drawer may be removed in the usual way, and thereafter replaced by merely inserting the drawer in the guides.

The drawer may be filled with papers and documents, and the guard serves to prevent loss into the waste spaces of the desk. Likewise a front guard may be provided which 10 may or may not have a spring 15 and stop members 12 and 14 corresponding to the back guard. The front guard may be swung upward, and the papers packed within the drawer in the usual fashion, whereafter the guard 15 may be swung downward, below the level of the drawer, compressing the papers into a desirably small bulk. The front guard may then be held manually in place, and the drawer closed. When so closed, the front guard 20 prevents the papers rising to the point of being caught behind the strip 16. They are thus protected against crumpling and displacement which otherwise occur if they are not held below the level of the drawer.

25 By this means I have provided a simple, inexpensive, convenient guard for drawers, which permits the drawer to be filled to maximum capacity without danger of displacement, loss, or injury of the contents. My device is simple to install and inexpensive to 30 make, and is convenient to use.

35 While I have shown but a single embodiment of the device of my invention in the accompanying description and drawings, it is capable of various modifications therefrom without departure from the inventive spirit thereof. For instance my invention may be applied to the slide of a desk or to a plurality 40 of drawers therein when one drawer is situated below the other. And I desire, therefore, that only such limitations shall be imposed upon the claims hereafter appended as are required by the prior art.

I claim as my invention:

1. In combination, a cabinet, a drawer 45 therein and a guard therefor comprising a transverse sheet metal strip pivoted to the rear part of the drawer with its free edge in proximity to the surface above the drawer, said strip having depending end pieces and 50 the latter being pivoted to the side walls of the drawer adjacent the end thereof, the dimension of said transverse member in the direction of the length of the drawer being slight as compared to the length of the 55 drawer.

2. In combination, a cabinet, a drawer therefor comprising a transverse member pivoted to the rear part of the drawer with its free edge above the 60 plane of the side walls of the drawer, said member being so placed as to span the space between the rear wall of the drawer and the surface of the cabinet above the drawer and to contact with the drawer guide of said cabinet to act as a stop for retaining the drawer against removal.

3. In combination, a cabinet, a drawer therefor and a guard for said drawer comprising a transverse member pivoted to the 70 rear part of the drawer with its free edge in proximity to the surface of the cabinet above the drawer, said member being so placed as to span the space between said surface and the rear wall of the drawer.

4. In combination, a cabinet, a drawer therefor and a guard for said drawer comprising a transverse member pivoted to the rear part of the drawer with its free edge in 80 proximity to the surface of the cabinet above said drawer, said member being arranged to span the space between said surface and the rear wall of the drawer, and spring means for holding said member in proximity to the 85 surface of the cabinet above the drawer.

In witness whereof, I hereunto subscribe my signature.

CHAS. H. J. DILG.
